UNITED STATES PATENT OFFICE.

BENJAMIN P. HAYES, OF KANSAS CITY, MISSOURI.

KEY.

1,415,029.

Specification of Letters Patent. Patented May 9, 1922.

Application filed April 13, 1921. Serial No. 461,132.

To all whom it may concern:

Be it known that I, BENJAMIN P. HAYES, a citizen of the United States, residing at Kansas City, in the county of Jackson and 5 State of Missouri, have invented certain new and useful Improvements in Keys; and I do declare the following to be a full, clear, and exact description of the invention, such as will enable others skilled in the art to 10 which it appertains to make and use the same, reference being had to the accompanying drawings, and to the figures of reference marked thereon, which form a part of this specification.

15 This invention relates to keys for digitally operated machines, and particularly to keys for use in connection with calculating machines.

One of the objects of the invention is to 20 provide a simple construction of key, the parts of which can be expeditiously assembled to provide a complete unitary structure.

It is also the object of the invention to inexpensively construct the key by a novel 25 means of assembling the key button and the post.

For convenience in description, I shall divide the key into two main parts; the key post, and the button to the secured thereto. 30 The particularly novel features of my invention will be apparent from reference to the following description in connection with the accompanying drawings, in which—

Fig. 1 is a perspective view of a key constructed in accordance with my invention.

Fig. 2 is a disassociated view of the several parts.

Fig. 3 is a sectional view through the key pad, the post being shown in elevation.

40 Fig. 4 is a sectional view through the key button showing the ferrule and card and pad in place preparatory to crimping the ferrule and card to the pad.

Fig. 5 is a similar view showing the ferrule and card.

Fig. 6 is a sectional view through the completed key.

The key post 1 may consist of a strip of material of appropriate configuration, depending upon the purpose for which it is to be used. At the upper end of the post, however, there is a restricted projection 2 which constitutes a rivet head whereby the key pad 3 may be secured to the post. The key pad is shown as consisting of a disk slightly concave at its upper face and provided with

a slot 4 to receive the projection 2 which may extend through the slot and be peened over to provide a head 5, (see Fig. 3). The disk or pad 3 is provided with a depending peripheral flange 6 to receive the cup-shaped ferrule 7, the inner diameter of which is approximately equal to the outer diameter of the pad. The ferrule or cap 7 is of transparent material; for example, celluloid, and within the ferrule is a card which may partake of the shape of the ferrule or cap, and which is provided with appropriate indicia, such as a number or letter, visible through the top of the ferrule or cap 7. The card 8 70 may be of paper or other appropriate material, and the card and ferrule are assembled as shown in Fig. 2. The ferrule is shown in Fig. 4 with its flange 9 extending below the flange or bead 6 of the pad 3, it being apparent that the card is provided with an apron or flange 10, which also extends below the flange 6, although in some instances, the apron or flange 10 may be omitted and the card may be simply a disk. In actual practice, however, I prefer to arrange the parts 75 as shown, so there will be a uniform appearance. As the ferrule and card are placed upon the pad 3, the extended edges may be crimped under the edge of the flange 6 and 80 within its perimeter as shown at 11, (Fig. 5). The next operation will be the assembling of the cup. The cup 12 is semispherical, and is provided with a curved, elongated slot 13 through which the post 1 may extend so that the upper edge 14 of the cup 85 may be forced against the face of the pad 3 and so that the edge portion or perimeter 15 of the cup may be peened against the crimping edge of the ferrule or cap 7 and hold it in 90 place as shown in Fig. 6.

It will be apparent from the foregoing that the key can be readily constructed and that it will be expeditiously assembled. The only machine operation after the parts are 100 formed will be the riveting or peening of the projection 2 to form the head 5. Thus the cost of the key will be materially reduced.

What I claim and desire to secure by Letters-Patent is:

1. A key comprising a post, a pad fastened to the post and having a depending peripheral flange, a ferrule seated on the pad and having a flange of greater width than that of the pad flange and crimped under the pad flange.

2. A key comprising a post, a key pad fastened to the post and having a peripheral flange, a ferrule seated on the pad and having a flange, the width of which is greater than the width of the flange of the key pad, the flange of the ferrule being crimped under the flange of the key pad, and a cup on the key post, having its outer surface bearing against the crimped under portion of the ferrule.
3. A key comprising a post having a constricted projection at one end, a pad comprising a disk provided with a slot and having a depending, peripheral flange, a rivet head on the post projection for holding the pad to the post, a ferrule and a card seated on the pad and having depending flanges of greater width than that of the pad flange and crimped under the edge of the pad flange.
4. A key comprising a post having a constricted projection at one end, a key pad comprising a disk provided with a slot, a rivet head on the projection for holding the pad to the key post, a ferrule and a card seated upon the pad and provided with depending flanges of greater width than that of the pad flange, the extending portions of the pad, the ferrule and card flanges being crimped under the pad flange, and a semi-spherical cup on a key post bearing against the crimped under portion of the ferrule, thus holding the ferrule and card in locked position with respect to the key pad.
5. A key comprising a post, a pad on the post, a card on the pad, and a transparent cap ferrule covering the card and having its edge crimped under the pad.
6. A key comprising a post, a pad on the post, an indicia card on the pad, a ferrule engaging the card and having a free edge crimped under the pad to hold the card in place, and a cup on the post beneath the pad, having a rim bearing against the crimped edge of the ferrule.
7. A key comprising a post, a key pad on the post, a ferrule on the pad of transparent material having its free edge crimped under the pad, and a cup on the post bearing against the crimped under portion of the ferrule to hold it in fixed position with respect to the pad.

In testimony whereof I affix my signature.
BENJAMIN P. HAYES.
